UNITED STATES PATENT OFFICE.

JOSIAH H. BYERLEY, OF RIVERSIDE, CALIFORNIA.

ENVELOPE-SEALING MACHINE.

Application filed July 18, 1923. Serial No. 652,231.

To all whom it may concern:

Be it known that I, JOSIAH H. BYERLEY, a citizen of the United States, residing at Riverside, in the county of Riverside and 5 State of California, have invented new and useful Improvements in Envelope-Sealing Machines, of which the following is a specification.

My invention relates to envelope sealing 10 machines, and a purpose of my invention is the provision of a comparatively simple and inexpensive machine for sealing envelopes which includes power operated means for successively moistening the flaps of envelopes and subsequently sealing the envelopes by pressing the flaps to closed position while the adhesive material of the flaps is moist.

My envelope sealing machine is designed 20 to feed the envelopes in packs on an inclined magazine with the envelopes resting on the bottom edge so that there is no danger of the contents falling out. The rotary arm engages the envelopes in succession by catching 25 underneath the flap and lifting each envelope in succession on to a tilting platform having spaced plates to allow the flap to hang downwardly. In this position the contents cannot fall out of the envelopes. The platform 30 is then slightly tilted bringing the flap into contact with a moistening roller and this roller by its engagement with the flap moistens the glue. The platform then tilts upwardly and on the succeeding movement 35 of the lifting arm is forced between the pivotally mounted presser plates to glue the flap to the body of the envelope and from thence the sealed envelopes are dropped by gravity into a receptacle.

Although I have herein shown and will 40 describe only one form of envelope sealing machine embodying my invention, it is to be understood that various changes and modifications may be made herein without departing from the spirit of the invention and the spirit and scope of the appended claims.

In the accompanying drawings,

Fig. 1 is a view in top plan showing one 50 form of envelope sealing machine embodying my invention.

Fig. 2 is a bottom plan view of the machine shown in Fig. 1.

Fig. 3 is a view showing in side elevation 55 the machine shown in the preceding views,

and Fig. 4 is a view similar to Fig. 3 showing the opposite side of the machine.

Figs. 5 to 8 inclusive are sectional views taken on the line 5—5 of Fig. 1 showing the various positions which the movable elements of the machine occupy during the operation of the machine.

Fig. 9 is a fragmentary sectional view showing another position of the envelope carrying device shown in Figs. 5 to 8. 65

Fig. 10 is an enlarged detailed view showing in top plan the carrying device comprised in the machine, the wall and a cam being shown in section, the view being taken on the line 10—10 of Fig. 5 and looking 70 downwardly as indicated by the arrows.

Fig. 11 is a plan view of the envelope carrying platform and the adjacent mechanism comprised in the machine.

Similar reference characters refer to similar parts in each of the several views. 75

Referring specifically to the drawings and particularly to Figs. 1 and 2, my invention in its present embodiment is shown as comprising a frame including side walls 15 and 16 rigidly held in spaced relation by cross bars 17. An envelope supplying magazine is arranged at one end of the frame between the walls 15 and 16, and this magazine includes a bottom plate 18 provided with slots 80 19 to receive fastening members 20 for adjustably sustaining side walls 21 upon the bottom wall so as to accommodate envelopes of various lengths. This magazine is inclined downwardly and inwardly toward the 85 frame with its inner end provided with a supporting flange 22 (Fig. 5) against which latter the envelopes are held in stacked relation by means of a follower 23.

A receptacle or magazine 24 is adapted to 90 receive the envelopes after they have been sealed, and this magazine is likewise provided with adjustable sides 25 to accommodate envelopes of various lengths, and the sides are slotted, as indicated at 26, to 95 facilitate the removal of the envelopes from the magazine.

As clearly shown in Fig. 5, a moistening device is arranged between the side walls 15 and 16, and this device in the present instance comprises a tank 27 containing water in which a roller 28 is adapted to be partly submerged. The roller is journaled in the tank so that a portion of its periphery projects above the tank for engagement with the 100 105 110

flap of an envelope. This roller is provided with a pulley 29 (Fig. 2) operatively connected to a similar pulley 30 by a belt 31. The pulley 30 is fixed to a shaft 32 suitably 5 journaled in the side walls 15 and 16 and having one end projecting beyond the frame and provided with a crank 33 by which the shaft may be rotated. It is, of course, understood that shaft 32 may be driven by a 10 motor or other suitable means without departing from the spirit of the invention.

As shown in Fig. 5, an arm 34 is fixed to the shaft 32 between the side walls 15 and 16 and adjacent the former, as clearly shown 15 in Fig. 2. This arm 34 is provided with a right angular extension 35 upon which is sustained an envelope carrying device comprising, as illustrated to advantage in Figs. 10 and 11, a pair of shafts 36 and 37, journaled in bearings 38 fixed to the extension 35, with the shaft 36 provided with a plate or tongue 39, and a shaft 37 with a pair of V-shaped plates or tongues 40. The left hand ends of the shafts 36 and 37 are provided with cranks 41 and 42, respectively, 20 carrying rollers 43 and 44, respectively. These rollers 43 and 44 are adapted to engage cams and are urged into engagement with such cams by means of springs 45 and 25 46, respectively, secured to the extension 35 and to the shafts 36 and 37 in the manner clearly shown in Fig. 10. The spring 45 is considerably stronger than the spring 46 for the purpose hereinafter described.

35 The cams engaged by the rollers 43 and 44 are illustrated to advantage in Fig. 5 wherein it will be seen that a cam is provided having a substantially semi-circular curved portion 47 and linear portion 48, and 40 a second curved portion 49. Arranged between the curved portions 47 and 49 is another cam having a curved intermediate portion 50, and an upwardly extending terminal lip 51 and a terminal portion 52. A third 45 cam is also provided upon which the roller 44 is adapted to work. This cam has a symmetrically curved intermediate portion 53 and abruptly curved terminal portions 54 and 55. All of the cams are in the form of 50 metal strips secured to the inner side of the wall 15 of the frame and in substantially encircling relation to the moistening device.

As shown in Figs. 1 and 5, a shaft 56 is journaled in the side plates 15 and 16, and 55 fixed to this shaft is a pair of arms 57 spanned by a platform comprising spaced plates 58. A U-shaped yoke 59 is fixed to the arms 57, and shafts 60 and 61 are journaled in this yoke, as clearly shown in Fig. 60 11. The shaft 60 carries a gripping plate 62. One end of the shaft 60 is provided with an extension 63 carrying a roller 64 which is adapted to engage an abutment plate 65. Fixed to the shaft 61 is a substantially Y-shaped lever 66 adapted for engagement

with the flap of an envelope, as will be more fully described hereinafter. The shaft 61 is provided with an angular extension 67 carrying a roller 68 adapted to engage a cam 69 fixed to the wall 15. The gripping plate 62 70 and the lever 66 are normally urged to the position shown in Fig. 5 wherein their rollers 64 and 68 engage the members 65 and 69. Springs 70 and 71 are associated with the shafts in the manner clearly shown in Fig. 75 11 to normally urge the members 62 and 66 to these positions.

A downward movement of the platform 58 toward the roller 28, and the operation of the gripping plate 62 and the lever 66 in a 80 fixed sequence is effected through the medium of an arm 72 (Figs. 1 and 3) fixed to the shaft 56 and carrying a roller 73 which is adapted to engage the periphery of a cam 74 fixed to the shaft 32.

For pressing the envelope flaps after they have been moistened and to thus effectively seal the envelopes, I provide a pressing device comprising a pair of presser plates 75 and 76 fixed to shafts 77 and 78, respectively, 90 journaled in the side plates 15 and 16. These plates are adapted to move from the position shown in Fig. 7 to the position shown in Fig. 5, and to effect such movement the following mechanism is provided: As shown in Figs. 1 and 3, the shaft 77 is provided with an arm 79 which is connected to a bell crank lever 80 pivoted at the point indicated at 81 and provided with a roller 82 which bears on the periphery of a cam 83 fixed to the shaft 32. The shaft 78 (Fig. 4) carries an arm 84 provided with a roller 85 which bears against the periphery of a cam 86 fixed to the shaft 32. The plates 75 and 76 are normally urged to the positions shown in Fig. 7 wherein it will be seen that the plate 75 constitutes in effect a continuation of a stationary plate 87 fixed between the walls 15 and 16, as clearly shown in Fig. 7. Springs 88 and 89 are associated with the shafts 77 and 78 for urging the plates to 100 these positions. As the result of such urging the rollers 82 and 85 are maintained in engagement with the peripheries of the cams 83 and 86 so that the cams serve to actuate the plates as will be understood.

The operation of the entire machine is as follows: The envelope supplying magazine is filled with envelopes arranged so as to have their flaps uppermost and at the machine side of the envelope. As the magazine is inclined the follower 23 serves to constantly urge the envelopes to the inner end of the magazine and thus at all times present the innermost envelope with its flap extended, as clearly shown in Fig. 5. With the envelope carrying device in the position shown in Fig. 5, upward movement of the latter is effected by actuating the arm 34 through the shaft 32. In this position of the carrying

device, the roller 43 engages the curved cam portion 47, and the roller 44 the curved cam portion 53, so that the tongues 39 and 40 are held in spaced relation, with the tongue 39 arranged to engage the innermost envelope beneath its flap so that as the arm 34 moves upwardly, the envelope will be lifted from the magazine. As the arm 34 proceeds upwardly, the tongues 39 and 40 move toward each other and into gripping relation with respect to the flap of the envelope. This movement of the tongues is effected by virtue of the fact that the roller 43 passes onto the linear cam portion 48, while the roller 44 rides over and off of the curved cam portion 54, thus allowing the tongue 40 to respond to the action of the spring 46. Continued movement of the arm 34 elevates the carrying device together with the envelope, and under the guidance of the curved cam portion 49, the tongue 39 is maintained in gripping relation with respect to the tongue 40 so as to carry the envelope onto the platform 58, it being understood that the tongues 39 and 40 pass between the plates of the platform. With the carrying device and the envelope now in the position shown in Fig. 6, the envelope reposes upon the plates of the platform so that upon continued movement of the carrying device, the roller 43 rides off of the curved cam portion 49, thus allowing the tongue 39 under the action of the spring 45 to move inwardly toward the shaft 32 thereby releasing the flap of the envelope so that the latter is now flat upon the platform. The envelope is maintained upon the platform by the gripping arm 62 which is moved to gripping position, as shown in Fig. 7, by the roller 64 disengaging the plate 65 upon downward movement of the yoke 59 so as to allow the spring 70 to actuate the shaft 60. The downward movement of the yoke 59 occurs with downward movement of the arms 57, the latter being actuated by the shaft 56 through the medium of the arm 72 and the cam 74. With such downward movement of the yoke 59, a similar movement is imparted to the lever 66 as its roller 68 disengages the cam 69, the lever now occupying the position shown in Fig. 7. During downward movement of the arms 57, the arm 34 continues to rotate thereby causing the roller 43 to ride off of the cam portion 49 and to immediately engage the cam portion 51 and subsequently the cam portion 50. Under the action of these cam portions the tongue 39 is swung inwardly and in so doing the envelope flap is unfolded or extended to the position shown in Fig. 7. The tongue 39 moves downwardly with the lowering of the platform so that the envelope flap is maintained in extended position for moistening by the roller 28. Continued movement of the arm 34 causes the tongue 39 to disen-

gage the envelope flap so upon continued lowering of the platform and lever 66, the flap is moved into contact with the roller 29, as clearly shown in Fig. 8. As the roller is constantly rotating, it will be clear that a moistening of the envelope flap is now effected.

The tongue 39 is moved out of engagement with the envelope flap under the guidance of the cam portion 52, but when the roller 43 leaves the cam portion 52 the spring 45 operates to throw the roller into contact with the outer surface of the cam portion 47, as illustrated in Fig. 9. During this movement, the shaft 37 is moved to thrust the roller 44 into engagement with the cam portion 55, and with further movement of the arm 34, the tongues 39 and 40 are finally returned to the normal position shown in Fig. 5.

During this movement of the arm 34, the arms 57 are elevated through the medium of the cam 86 so as to return the platform 58 to the elevated position shown in Fig. 6. With the return of the platform, the yoke 59 is likewise elevated so as to move the gripping arm 62 and the lever 66 back to normal position. As soon as the lever 66 disengages the flap of the envelope, the flap returns to partly folded position, as shown in Fig. 5.

While the platform 58 is in the elevated position, the arm 34 in its continued movement elevates the tongues 39 and 40 to engage the flap of the second envelope and elevate the envelope to the platform 58, as shown in Fig. 6. As this second envelope moves onto the platform, the tongues 40 engage the edge of the first envelope and ultimately project the first envelope from the platform and downwardly onto the plate 87. As the plate 87 is inclined, the envelope will slide downwardly onto the lower pressing plate 75 when the cams 83 and 86 will operate to move the pressing plates toward each other, as shown in Fig. 5, thereby pressing the flap to closed position and effecting the sealing of the envelope. Continued movement of the cams allows the pressing plates to remain in this pressing position for a period sufficient to insure of the effective sealing of the envelope when the plates are returned to normal position thereby releasing the envelope and allowing the latter to drop into the receiving magazine 24. It will be understood that during this sealing operation the second envelope is manipulated by the levers, tongues and platform to moisten the flap thereof in the same manner as the first envelope, and this second envelope is finally returned to the platform and ultimately delivered to the pressing plates in the same manner as the first envelope.

From the foregoing operation, it will be

clear that the machine continuously operates to singly remove envelopes from the supply magazine and to successively moisten and seal the flaps thereof, and to deliver such sealed envelopes to the receiving magazine 24.

An important feature of my invention is the automatic delivery of the envelopes to the discharge end of the supply magazine 10 by means of inclining the magazine and providing the rolling follower, the latter serving to maintain the envelopes in vertical position so that the foremost envelope presents its flap into engaging relation with 15 respect to the tongue 39.

Another important feature of my invention is the provision of an envelope sealing machine which utilizes the flaps of the envelopes to feed the latter to the moistening device so that irrespective of the thickness 20 of the envelopes, a positive feeding of the envelopes to the platform is effected.

It will be noted that the envelopes fed in the feeding magazine rest on their lower 25 edge so that there is no danger of the contents dropping out and when positioned on the tilting platform 58 the contents will still be retained in the envelope due to the position shown in Fig. 5. As this platform 30 is depressed as shown in Figs. 7 and 8, the gripping plate 62 presses the envelope to prevent the contents slipping out, as the flap is bent back during the feeding shown in Fig. 6, the contents are held in position 35 while the envelope passes between the presser plates 75 and 76 and thereby sealed. Hence from start to finish there is no danger 40 of any of the contents, no matter how loosely positioned in the envelope or what enclosures may be inserted, slipping out and becoming lost. Therefore my machine is adapted to seal the envelopes for many commercial purposes for which the usual type are unsuited.

What I claim is:

1. An envelope sealing machine comprising in combination a feeding magazine adapted to feed the envelopes on their lower edge with their flaps extending forwardly, a platform above the magazine, means to elevate the envelopes to said platform, a dampening device, means to bring the dampening device and the envelope flap into engagement, means to discharge the envelope from the platform and sealing means below the platform to press the flap against the envelope.

2. An envelope sealing machine comprising in combination a feeding magazine adapted to feed the envelopes on their lower edge with the flaps extending forwardly of each envelope, a shifting platform above the magazine, means to engage the envelopes by the flaps and elevate them to the said platform, a moistening device located below the platform, means to lower the platform

whereby the flap is brought into operative engagement with the moistening device, means to elevate the platform, a pair of presser plates, means to force the envelope from the platform to the presser plates to 70 seal the flap and means to discharge the envelope therefrom.

3. An envelope sealing machine comprising in combination a magazine adapted to feed envelopes on their lower edge with the 75 flaps extending forwardly of each envelope, a tilting platform above the magazine, a rotary arm having means to engage each envelope by its flap and lift the envelope to the platform, a roller moistening device positioned below the platform, means to tilt the platform downwardly bringing the flap into contact with the moistening roller, means to elevate the platform, a sealing device comprising a pair of oppositely positioned pivotally mounted presser plates, means on said rotary arm to force an envelope off the tilting platform to the sealing device and means to cause a discharge of 80 the envelope therefrom.

4. An envelope sealing machine as claimed in claim 3, in which the rotary arm has a swivelling tongue extending laterally therefrom adapted to engage the envelope flaps, a cam to control the movement of said tongue 95 and a second tongue to operate the discharge of envelopes and the cam to control the said second tongue.

5. An envelope sealing machine, comprising a moistening device, an envelope supply 100 magazine, an envelope receiving platform mounted for movement, means for moving a single envelope from said magazine and conveying the same to said platform, gripping means for maintaining the envelope 105 on said platform, means for actuating the platform to move the envelope toward said moistening device, means coacting with the envelope conveying means for completely opening the flap of said envelope so that 110 the latter is engaged by the moistening device, means for returning the platform to normal position and for simultaneously releasing the envelope and allowing the flap to return to folded position, and means for 115 pressing the flap of the envelope to closed position after such release.

6. An envelope sealing machine, comprising a movable platform to which envelopes 120 are adapted to be singly delivered, a moistening device, envelope gripping means for maintaining the envelope on said platform, means for actuating the platform to move the envelope toward and away from the moistening device, means for opening the flap of said envelope as the latter is moved toward the moistening device so that the device effects moistening of the flap, and means for receiving the envelope and pressing the flap to closed position.

7. An envelope sealing machine, comprising a moistening device, an envelope supply magazine, a platform movable away from and toward the moistening device, rotary means for successively carrying a single envelope from said magazine and depositing same on said platform, gripping means for maintaining the envelope on said platform, means coacting with the rotary means for 10 opening the flap of said envelope so that when the platform moves toward said moistening device a moistening of the flap is effected, means for actuating gripping means for releasing the envelope, and means for 15 receiving and pressing the envelope to effect the sealing of the flap.

8. An envelope sealing machine, comprising a moistening device, a platform movable toward and away from the moistening device, an envelope supply magazine, a gripping device mounted for rotary movement, means for actuating the device to cause the same to engage a single envelope in the magazine by its flap and carry the same to 20 said platform, means for maintaining the envelope on said platform, means for actuating rotary gripping means for opening the flap of said envelope so that when the platform moves toward the moistening device, the flap will be moistened, and means for receiving and pressing the flap to seal the envelope when the envelope is removed from said platform.

9. An envelope sealing machine, comprising a moistening device, a platform movable toward and away from the moistening device, an envelope supply magazine, an envelope carrying device movable to engage and carry an envelope from the magazine to 35 said platform, means for temporarily maintaining the envelope on said platform, means coacting with the envelope carrying means to open the flap of said envelope, means for receiving and pressing the flap of said envelope, and means carried by the envelope carrying means for forcing an envelope from 40 said platform to said pressing means.

10. In an envelope sealing machine, a tilting platform adapted to support an envelope 50 with the flap extending forwardly therefrom, a moistening roller positioned below the platform, means to tilt the platform to bring the flap into engagement with the moistening roller, means to press the flap 55 against the roller whereby the roller moistens the flap, means to elevate the platform and means to seal the moistened flap.

11. An envelope sealing machine, comprising

ing an envelope supply magazine, an envelope receiving magazine, a moistening device, a platform movable toward and away from said moistening device, means for successively removing an envelope from the supply magazine and delivering the same to said platform, means for actuating the 60 platform after a single envelope has been deposited thereon to cause the flap thereof to be moistened by said device, means coacting with the first means for opening the flap of the envelope so that the latter will 65 be moistened by said device, envelope pressing means arranged above the envelope receiving magazine so that when said means is in release position the envelope will gravitate into the magazine, and means carried 70 by the first means for projecting an envelope from the platform to said pressing means.

12. An envelope sealing machine comprising in combination a magazine adapted to feed envelopes on their lower edge with the 75 flaps extending forwardly, a tilting platform supported above the magazine secured to a shaft at one side thereof, a rotary arm having a pivotally mounted lifting tongue on the end adapted to engage the projecting flaps, a track-like cam controlling the motion of the lifting tongue to lift the envelopes on to the platform, a moistening roller below the platform, means to tilt the shaft and lower the platform adapted to bring the 80 flaps into engagement with the roller the flap being guided by the lifting tongue, said latter being controlled by a second cam track during this phase of the operation, a second 85 tongue pivotally mounted on the end of the rotary arm and controlled by an arcuate track to disengage the said tongues one from the other and springs controlling the action of the tongues to swing them together to grip the flaps on both sides thereof, said second tongue being constructed and shaped to force an envelope off the platform 90 after said platform has returned to its original position into a sealing device.

13. An envelope sealing machine as 95 claimed in claim 12 having in addition a sealing device having a stationary plate and a pair of presser plates with operative shafts on opposite sides of the said plate whereby the free ends of the presser plates swing 100 towards each other and towards their respective shafts.

In testimony whereof I have signed my name to this specification.

JOSIAH H. BYERLEY.
